HAND LOOM FOR MAKING WOVEN STRIPS

Opal Eisenbeis, 221 N. Union, Madison, S. Dak. 29660

Filed July 10, 1970, Ser. No. 23,895

Term of patent 14 years

Int. Cl. D15—06

U.S. Cl. D92—15

FIG. 1

FIG. 2

FIG. 3

FIG. 4

FIG. 1 is a side perspective view of a hand loom for making woven strips showing my new design;

FIG. 2 is an end view thereof;

FIG. 3 is a top plan view; and

FIG. 4 is a side elevational view.

I claim:

The ornamental design for a hand loom for making woven strips, substantially as shown.
